4 Sheets-Sheet 3

Fig. 4: A side-view technical drawing of a mechanical assembly. The assembly consists of a vertical frame with a horizontal top beam (7) and a horizontal bottom beam (23). A central vertical column (5) supports a series of horizontal plates (8, 9, 10, 11, 12, 13, 14, 15, 16, 17, 18, 19, 20, 21, 22, 23, 24). A horizontal beam (24) is attached to the top of the frame. A diagonal member (A) is attached to the frame. A lower section shows a base with supports (18, 19) and a central vertical column (6) with a horizontal plate (20) attached. A label '18' is also present on the base.

Fig. 5: A detailed view of a circular component, likely a wheel or pulley. It features a central hub (10) with a bearing (3) and a flange (6). The flange has a slot (24) and a curved track (25). A cable (11) is attached to the flange. The hub has a slot (12) and a curved track (25). The entire assembly is mounted on a frame (5).

UNITED STATES PATENT OFFICE.

PLUMB R. GOSS, OF KANSAS CITY, MISSOURI.

STORE-SERVICE APPARATUS.

Application filed April 9, 1927. Serial No. 182,257.

My invention relates to improvements in store service apparatus.

One of the objects of my invention is to provide a novel apparatus for the display and serving of merchandise, easily, quickly and with a minimum of labor.

A further object of my invention is to provide a service apparatus of the kind described, which is simple, cheap, strong, durable, of ornamental appearance, which enables a larger amount of merchandise to be stored in small space, which enables customers to be quickly and satisfactorily served, which enables the display of a large variety of goods, and which is efficient in operation.

A further object of my invention is the provision of a novel serving car and supporting means therefor, with which a clerk can quickly assemble and transport purchased goods from the shelves to the delivery counter.

The novel features of my invention are hereinafter fully described and claimed.

In the accompanying drawings, which illustrate the preferred embodiment of my invention,

Fig. 1 is a plan view of my improved apparatus.

Fig. 2 is a section on the line 2—2 of Fig. 1.

Fig. 3 is a section on the line 3—3 of Fig. 1.

Fig. 4 is a section on the line 4—4 of Fig. 1.

Fig. 5 is a section on the line 5—5 of Fig. 4.

Fig. 6 is an enlarged inside elevation of the car and a portion of the frame which supports the car.

Similar reference characters designate similar parts in the different views.

My apparatus provides, in the preferred form shown, two parallel tiers of shelves 1 and 2, which are spaced to form between the tiers a passage 3. Each tier may comprise a plurality of vertical rows of shelves, each shelf being pivoted on a vertical axis so as to swing into the passage 3 over the path of a suitable serving car 4 adapted for travel in the passage 3 parallel with the tiers.

For supporting the shelves 1 an upright frame A is provided having inner supporting posts 6 and outer posts 5, the posts 5

and 6 being mounted on the floor and connected at their upper ends by a horizontal plate 7.

The upper portion of each post 6 is preferably square in cross section and is adapted to have mounted on it, one above the other, supporting members 8 supported by and held clamped to the post and to clamping plates 10 by bolts 9. By loosening the bolts 9, the members 8 and plates 10 may be independently vertically adjusted on the post.

The shelves 1 are respectively supported by the members 8 upon which they rest, and they are pivoted thereto on a vertical axis by means of a vertical rod 11 which extends through the members 8 of each vertical row and on which the shelves 1 are adapted to swing from the position shown in solid lines in Fig. 5, to the position shown in dotted lines in said figure, and in the last named position being disposed over the path of travel of the serving car 4.

For limiting the inward swinging of the shelves 1 of each row, there are provided vertical bars 13 on the frame A, one bar for each vertical row of shelves, and arranged to limit the movement inwardly of the shelves in that row to the position shown in solid lines in Fig. 5. For limiting the outward swinging of the shelves, the forward edge of each shelf 1 has a notch 12 adapted to receive the adjacent post 6.

For supporting the car 4, the frame A has fastened to it a longitudinal bar comprising a horizontal angle bar 14, one flange of which extends laterally into the passage 3 and has mounted on it two carrying wheels 15, which are rotatable on horizontal axes, and are disposed at one side of the car, next to the frame A.

The frame A at its inner side has a horizontal angle bar 16, which is above and parallel with the bar 14, and which has a downwardly extending flange the inner side of which is engaged by rollers 17 rotatable on the side of the car 4. Two rollers 18 are rotatable on vertical axes on the lower end of the car 4. The rollers 18 are, preferably, grooved rollers and have disposed in them the lateral flange of the angle bar 14. A plate 19 fastened to the car 4 intermediate of the rollers 18 slidably engages the angle bar 14 at the side thereof opposite to that engaged by the rollers 18. The plate 19 pre-

vents the lower end of the car from swinging off from the bar 14. The angle bars 14 and 16 serve as rails for the car.

The car 4 may be provided at its ends 5 with steps 20 and 21 upon which the server of the merchandise may step in order to have access to the upper shelves 1 and 2.

The shelves 2 are mounted on a frame B, similar to and parallel with the frame A, 16 and having posts 5 and 6 corresponding in construction and function to the posts 5 and 6 of the frame A, the posts 6 having supporting members 8 carrying the shelves 2 and rods 11 on which the shelves 2 are pivoted to swing over the path of the car 4, the members 8 on the frame B being held clamped to the posts 8 by plates 10 and bolts 9, as described with reference to corresponding elements on the frame A.

20 The frame B is also provided with the vertical rear stop bars 13 adapted to engage the shelves 2.

As shown in Figs. 1 and 2, a horizontal longitudinal plate 22 has its ends pivoted to the frame B, so that it may be swung from an edge up position, shown in dotted lines in Fig. 2, to a horizontal position, shown in solid lines in Figs. 1 and 2, in which latter position, the plate may serve as a step upon 30 which the operator may stand.

At one end of the frames A and B is a U shaped counter having a transverse portion 23 which is at the end of the passage 3, and which is spaced from the frames A and B, so 35 that a clerk may serve goods to a customer, while the car 4 is being used by another clerk in assembling merchandise called for. The arms 24 of the counter are respectively alined with the frames A and B.

40 By loosening the bolts 9, the shelves and their supporting members 8 may be independently vertically adjusted so as to be spaced apart, as desired.

In the operation of the invention, a clerk 45 may remove the goods from the shelves 1 and 2, the latter being swung into the passage for this purpose, and then swung back into the frames. The goods removed are mounted on the car 4, and the latter, when loaded 50 is moved along its track comprising the rail bars 14 and 16 to the position, shown in Fig. 1. The operator may then pass around the car to a position between the car and the counter, and unload the articles upon the 55 counter, or another operator stationed next the counter may remove and serve the goods.

The arms of the counter may be fastened to and supported upon the frames A and B forward of the shelves 1 and 2, as shown in 60 Figs. 1, 3 and 4. The counter prevents purchasers or others passing into the passage at the front end thereof.

To conserve space, each shelf 1 and 2 may have, in plan, the form of the quadrant of a

circle, the arcuate portion being concentric 65 with the axis of the shelf, as shown. Each shelf may have, as shown in Figs. 1, 3 and 5, an upstanding peripheral flange 25 for retaining the merchandise on the shelf.

I do not limit my invention to the structure 70 shown and described, as many modifications, within the scope of the appended claims may be made without departing from the spirit of my invention.

What I claim is:—

1. In a store service apparatus, two oppositely disposed tiers of shelves, a U-shaped counter at one end of and having its arms respectively alining with said tiers, supporting means for said shelves, and a car 80 arranged to run on said supporting means between and closely adjacent to said tiers and the arms of said counter.

2. In a store service apparatus, two oppositely disposed tiers of shelves having a passage between them, supporting means for said shelves having a longitudinal track at one side of said passage, a U-shaped counter having its arms respectively alined with said tiers and extending substantially to the vertical plane of the adjacent ends of said tiers, said track extending between said arms, said passage terminating at the transverse portion of said counter, the latter being spaced from said tiers, and a car adapted for travel 95 in said passage on said track.

3. In a store service apparatus, two oppositely disposed tiers of shelves with a passage between them, supporting means for the shelves on which the shelves are each pivoted on a vertical axis so as to swing into and out of said passage, and a car adapted to travel in said passage on said supporting means closely adjacent to said tiers.

4. In a store service apparatus, two oppositely disposed tiers of shelves having a passage between them, supporting means for the shelves on which said shelves are each pivoted so as to swing into and out of said passage, a counter closing said passage at one 110 end of said tiers, and a car adapted for travel on said supporting means in said passage adjacent to said tiers.

5. In a store service apparatus, two oppositely disposed tiers of shelves having between them a passage, supporting means to which said shelves are pivoted so as to swing into and out of said passage, a U-shaped counter having its transverse portion closing said passage and spaced from said tiers and 115 having its arms respectively alined with and extending substantially to said tiers, and a car adapted for travel in said passage on said supporting means between said arms and said tiers.

In testimony whereof I have signed my name to this specification.

PLUMB R. GOSS.
